Elimir J. Ney, of Lowell, Mass.
Assignor to
The Lowell Manufacturing Company,
Letters Patent No. 1649, dated Aug. 12, 1862,
~~~~~

The schedule referred to in these Letters Patent and making part of the same.

To all whom it may concern;

Be it known that I, Elimir J. Ney, of Lowell,
in the County of Middlesex, and State of Massachusetts, have originated
and designed a new pattern for carpets or other fabrics, of which the
following is a full, clear and exact description, reference being had to
the accompanying drawings, making part of this specification.

A, is one half of a set figure resting on a ground
of net work, which is surrounded by a rope like frame supporting
four heavy leaves. In corners 1 and 2, are fourths of crop shaped
figures resting on a ground of mottled work which is enclosed by
a frame of scrolls.

Running from
fig 3, at the top of the design, to corners 4 and 5, is the key work band 7, on
each side of which lies regular ground work of lines and dots.

The colors employed for the different portions of the
design may be varied to suit the taste & wish of the manufacturer.

Claim

What I claim as my invention and desire to se-
cure by Letters Patent, is the design or pattern for carpets or other fabrics, herein set forth.
